[57] CLAIM

The ornamental design for a dental bite tray, as shown and described.

DESCRIPTION

FIG. 1 is a top perspective view of a dental bite tray showing my new design;

FIG. 2 is a top plan view thereof;

FIG. 3 is a bottom plan view thereof;

FIG. 4 is a side elevational view, the opposite side being a mirror image thereof;

FIG. 5 is an elevation as viewed from the closed end of the tray;

FIG. 6 is an elevation as viewed from the open end of the tray; and,

FIG. 7 is a cross-section as taken on line 7—7 of FIG. 2.
